UNITED STATES PATENT OFFICE

OTTO E. UHLMANN, OF GRAND RAPIDS, MICHIGAN, ASSIGNOR TO KEELER BRASS COMPANY, OF GRAND RAPIDS, MICHIGAN

DESIGN FOR A HANDLE FOR A DOOR OF AN AUTOMOBILE OR THE LIKE

Application filed January 12, 1931. Serial No. 38,285. Term of patent 3½ years.

To all whom it may concern:

Be it known that I, OTTO E. UHLMANN, a citizen of the United States, residing at the city of Grand Rapids, in the county of Kent and State of Michigan, have invented a new, original, and ornamental Design for a Handle for a Door of an Automobile or the like, of which the following is a specification, reference being had to the accompanying drawings, forming a part thereof.

Fig. 1 is an end elevational view, and Fig. 2 is a front elevational view, and Fig. 3 is a top elevational view of a door handle, showing my new design.

I claim:

The ornamental design for a handle for a door of an automobile or the like, as shown.

OTTO E. UHLMANN.
